UNITED STATES PATENT OFFICE.

ALFRED HENRY ROWE, OF WINNIPEG, MANITOBA, CANADA.

SCRUBBING-MACHINE.

1,393,453.

Specification of Letters Patent.

Patented Oct. 11, 1921.

Application filed April 26, 1920. Serial No. 376,693.

To all whom it may concern:

Be it known that I, ALFRED HENRY ROWE, of the city of Winnipeg, in the Province of Manitoba, Canada, have invented certain new and useful Improvements in Scrubbing-Machines, of which the following is the specification.

The invention relates to improvements in scrubbing machines and the object of the invention is to provide a motor driven machine which when in operation will scrub the floor, the attendant only requiring to guide the machine from place to place.

A further object is to construct the machine so that the brush thereof can be adjusted in height and so that the water used in scrubbing will be carried by the machine and directed to the brush and toward the floor in controlled quantities.

With the above more important objects in view the invention consists essentially in a frame mounted on suitable carriage wheels, a motor driven brush adjustable in respect to the floor, a water tank and means for feeding water from the tank to the brush in limited quantities, the parts being arranged and constructed as hereinafter more particularly described and later pointed out in the appended claims, reference being had to the accompanying drawing in which:—

Figure 1 is a side view of the complete machine.

Fig. 2 is a plan view thereof.

Fig. 3 is a vertical sectional view centrally through the front end of the machine.

Fig. 4 is a sectional view at 4—4', Fig. 1 and looking forwardly.

Fig. 5 is a horizontal sectional view at 5—5' Fig. 3 and looking downwardly.

Fig. 6 is an enlarged vertical sectional view through the front end of the water tube.

In the drawing like characters of reference indicate corresponding parts in the several figures.

1 represents a frame presenting a platform carried forwardly by a pair of carriage wheels 2 and 3 and rearwardly by a swiveled caster wheel 4 which is arranged so that it can be steered by an extending handle 5. In the present instance slots are made in the frame to let the front wheels project through and the said wheels are rotatably mounted on the ends of an axle 6 permanently bolted to the underside of the

frame. The above parts form a carriage which can be steered about the floor as desired.

In a location directly adjoining the front wheels I locate a pair of upright guides 7 and 8 which have their lower ends permanently secured to the sides of the frame and their upper ends connected by a cross head 9. The guides receive slidably a vertically disposed head plate 10 which is supported 65 and adjustably suspended by means of a centrally disposed jack screw 11 carried by the cross head 9 and fitted with a hand wheel 12.

To the lower end of the head plate 10 I secure permanently a forwardly extending 70 bracket or auxiliary platform 13 which carries parts later disclosed.

14 is an electric motor permanently secured to the head plate and having the drive shaft 15 thereof located in an upright position and fitted at the lower end with a driving pinion 16 which is adapted to continuously mesh with a gear wheel 17 secured to the upper end of the brush shaft 18 which is rotatably carried in the bracket and projects through the frame 1 in a position centrally in advance of the front wheels. 19 is a circular brush secured permanently to the lower end of the shaft 18 and engageable with the floor to be scrubbed.

20 and 21 are the customary electrical feed wires leading to the motor. These wires are fitted with the usual screw plug (not shown) whereby the motor can be connected with the usual electric socket provided in a 90 room.

Obviously by the arrangement shown one by turning the hand wheel 12 can adjust the head plate with the result that the brush can be raised or lowered in respect to the floor. 95 On the rear part of the frame I mount a water tank 22 fitted with a removable cover 23. 24 is a water feed pipe communicating with the bottom of the tank and extending forwardly of the platform in a location beneath the bracket and having the forward end extending downwardly through the platform and terminating in a location in advance of the brush and just clear of the floor. The forward end of the pipe is 105 obliquely cut away as shown in Fig. 6 so that the water naturally discharges on to the floor and on to the brush. The discharge of the water is controlled by a valve 25 and one by turning the valve a greater 110

or less amount obviously controls the feed of the water from the tank to the brush and floor. 26 is a guard plate secured to and passing around the front end of the platform and inclosing the brush, thus preventing the water thrown off the brush by centrifugal force from splashing around the room.

When the device is in use one opens the 10 valve a predetermined amount and then guides the machine over the floor, steering it by the handle 5. The rotating brush in contact with the floor effectively scrubs the floor loosening all dirt thereon.

15 After one has used the machine on the floor he simply mops up the water in the ordinary way.

What I claim as my invention is:—

1. A scrubbing machine comprising a 20 main supporting platform, a water tank mounted thereon, vertical guides extending from the platform forwardly of the tank, an adjustable supporting structure carried between said guides, a brush located beneath 25 said platform and suspended from said supporting structure so as to be movable with the latter, and an outlet from the tank extending forwardly upon the platform beneath the supporting structure to a point in 30 advance of said supporting structure, the discharge end of said conduit being extended downwardly through the platform to a point directly in advance of the brush and being

provided with a discharge orifice arranged directly opposite the brush bristles. 35

2. A scrubbing machine comprising a main supporting platform provided with a vertical aperture forming a bearing, a vertical shaft slidable in said bearing and equipped at its lower end with a brush, a motor 40 geared to the upper end of said shaft, and adjustable means serving to support both the motor and the brush shaft whereby the latter may be adjusted vertically without disturbing its operative connection with the 45 motor.

3. A scrubbing machine comprising a portable main supporting platform provided with a vertical aperture forming a bearing, a vertical shaft slidable in said bearing and equipped at its lower end with a brush adapted to rotate with the shaft, an auxiliary platform supported on the main platform and vertically adjustable thereon, said shaft being suspended at its upper end 55 from said auxiliary platform so as to be adjusted therewith, and a motor carried by said auxiliary platform and having its shaft geared to the brush shaft.

Signed at Winnipeg, this 26 day of March, 60
1920.

ALFRED HENRY ROWE.

In the presence of—
GERALD S. ROXBURGH,
K. B. WAKEFIELD.
